BELT-ATTACHED TOOL HOLDER

George E. Kuehl, 616 E. 16th Ave.,
Eugene, Oreg. 97401

Filed Sept. 23, 1974, Ser. No. 508,086

Term of patent 14 years

Int. Cl. D2—07

U.S. Cl. D2—400

FIG. 1 is a front perspective view of a belt-attached tool holder showing my new design;

FIG. 2 is a front elevational view thereof, the rear being substantially similar thereto with the exception that the two vertical side members would be continuous parallel lines;

FIG. 3 is a top plan view of FIG. 2;

FIG. 4 is a right side elevational view thereof; and

FIG. 5 is a bottom plan view of FIG. 4.

The rear of the article is substantially as viewed in FIG. 2 with the exception that the two vertical side members are defined by unbroken pairs of parallel lines.

I claim:

The ornamental design for a belt-attached tool holder, as shown and described.
